UNITED STATES PATENT OFFICE.

GASTON DE BETHUNE, OF BRUSSELS, BELGIUM.

APPARATUS FOR THE MANUFACTURE OF PIG IRON.

Application filed July 15, 1925, Serial No. 43,854, and in Belgium March 5, 1925.

The subject of this invention is the introduction, into furnaces or blast furnaces which they are working, of materials or residues of various kinds which either increase the production of pig iron or modify the working of the said furnaces or blast furnaces.

The introduction, according to the method claimed by the invention, of these materials, the nature of which may vary according to 10 the case and which are previously crushed or pulverized, enables in particular the basicity of the slags and the internal temperatures of the furnace to be increased or decreased rapidly, and the composition of the gases produced by the latter to be varied. In the case where the materials introduced are ores or the residues of ores, the method according to 15 the invention enables the output of the furnace to be increased, use being made of materials which are generally thrown away in spite of their value.

The present invention relates to apparatus serving for the introduction, especially into blast furnaces or the like of comminuted material either pulverized or otherwise, and including a plurality of tuyères disposed coaxially one within the other from one or more of which a jet of air under pressure is delivered, assuring the entrainment and injection 20 of the material to be introduced into the furnace.

The utilization of unheated air under pressure presents the inconvenience on the one hand of unduly cooling the interior of the blast furnace and producing in consequence, divers derangements in the operation of the furnace or the character of the product, and on the other hand, through the humidity of the unheated air, producing the adherence of 25 material to the tuyères, partially or wholly occluding them, unless the unheated air has been previously dessicated.

It may be observed on the other hand, that if the air is heated, its density is too slight to 30 assure sufficient velocity for the proper entrainment of the material, unless the air is injected in such great quantity as to considerably accelerate combustion within the furnace, under which conditions it follows that 35 the pressure of the furnace is augmented to such an extent as to diminish yet further, the efficiency of the current of heated air as a vehicle for the introduction of the comminuted material.

88 The invention consequently has for its ob-

ject the utilization of the advantages resulting from the employment both of heated air and of unheated air, and in avoiding at all times the disadvantages of each when used separately.

With this end in view it is contemplated to make use of heated air in order to improve the output of the furnace and to avoid the accumulation of material in the tuyères which is never produced under heated air conditions, and to utilize equally, a certain proportion of unheated air under relatively high pressure to assure the entrainment of the material.

This purpose is realized following the principles of the invention, by means of an apparatus including a tuyère having two cylindrical portions of different diameters each terminating in a nozzle having the shape of a truncated cone. The cylindrical portion of greater diameter receives the material, which is entrained by two injectors disposed coaxially, the outer injector delivering the heated air and the inner or more centrally located injector delivering the unheated air under pressure, the whole that is to say, both jets of air, with the entrained material, being delivered to the blast furnace by means of a conical portion terminating in a cylindrical portion of small diameter, the walls of which are cooled by circulation of water, it being understood that the jet of heated air envelops the jet of unheated air so as to substantially keep the latter out of contact with the walls of the tuyères, thereby avoiding the chilling of said walls and the depositing thereupon of condensed matter.

The advantages and characteristics of the invention are set forth in the following description of the sole figure which represents in cross section a tuyère with the associated injectors embodying the principles of the invention.

Referring now in detail to the figure, the apparatus consists of a tuyère 1 with hollow walls in which circulates water, with inlet and outlet pipes 2 and 3 above which opens out a channel 4 which admits the materials which are to be introduced in the form of dust; the delivery through this duct 4 is regulated by a suitable valve 5; the inner wall of the said tuyère is also protected by a removable part 6.

In order that the materials fed in the tuyère 1 will be carried along, hot draught and compressed air injectors are provided.

In the form of construction shown the said injectors are arranged co-axially in the interior of the part above the tuyère 1.

In the first place use is made of an injector 5 with a conical mouth-piece through which is delivered the hot draught which is led through a pipe 8 provided with a suitable valve 9. In the interior of the above mentioned injector is placed a second injector 10 with a conical mouth-piece, through which is delivered the compressed air passing through a pipe 11 provided with a suitable valve 12. Manometers 13 are provided on the compressed air pipe, the hot draught pipe and 15 also on the tuyère 1 so as to indicate the value of the pressures and partial vacuums produced in these pipes.

It will be seen that it is possible to modify the introduction of the materials in a perfect 20 manner by regulating the valves 5, 9 and 12 and that in certain cases the apparatus may serve for introducing either a hot draught and compressed air or if desired gases under pressure; similarly, the materials carried 25 along may in certain cases only consist of either fuel, or a fuel mixed with certain melting materials such as limes, sand, magnesia and the like.

What I claim is:

30 1. Apparatus for the introduction into furnaces of comminuted material, comprising a

tuyère including two cylindrical portions of different diameters having an intermediate tapering portion, a channel delivering the material to the cylindrical portion of greater 35 diameter, an injector delivering heated air to the interior of said tuyère below said channel, a second injector disposed coaxially on the interior of the first and delivering unheated air under pressure, the second cylindrical portion delivering material to the interior of the furnace having relatively great 40 length and relatively small cross section and including means for cooling the walls thereof.

2. Apparatus for the introduction into furnaces of comminuted material, comprising a tuyère including two cylindrical portions of different diameters having an intermediate tapering portion, a channel delivering material into the cylindrical portion of greater 45 diameter, and an injector delivering heated air to said tuyère below said channel, a second injector disposed coaxially of the interior of the first injector and delivering unheated air under pressure, the second cylindrical portion 50 delivering the material to the interior of the furnace having a relatively great length and relatively small cross section, the walls being cooled by the circulation of water.

In testimony whereof I have signed my 55 name to this specification.

GASTON DE BETHUNE.
